(57) **CLAIM**

The ornamental design for a golf club shaft extender with lattice pattern on insert end, as shown and described.

DESCRIPTION

FIG. 1 is a top perspective view of a golf club shaft extender with lattice pattern on insert end, and showing our new design;

FIG. 2 is a bottom perspective view thereof;

FIG. 3 is a side elevational view thereof, the opposite side view being a mirror image thereof;

FIG. 4 is a side elevational view of FIG. 3 rotated 90 degrees about the central axis thereof;

FIG. 5 is a sectional side view thereof, the section taken along lines 5—5 shown in FIG. 4;

FIG. 6 is a top plan view thereof; and,

FIG. 7 is a bottom plan view thereof.
